UNITED STATES PATENT OFFICE.

JUSTUS P. SEEBURG, OF CHICAGO, ILLINOIS.

DESIGN FOR AN ORCHESTRION-CASE.

44,593.

Specification for Design.

Patented Aug. 26, 1913.

Application filed May 22, 1913. Serial No. 769,300. Term of patent 14 years.

To all whom it may concern:

Be it known that I, JUSTUS P. SEEBURG, a citizen of the United States, residing at Chicago, in the county of Cook and State of Illinois, have invented a new, original, and ornamental Design for Orchestrion-Cases, of which the following is a specification, reference being had to the accompanying drawing, forming part thereof.

The figure is a perspective view of an orchestrion case, showing my new design.

I claim:

The ornamental design for orchestrion cases, as shown.

JUSTUS P. SEEBURG.
